APPARATUS FOR SEPARATING AND, IF DESIRED, SORTING FLAT CIRCULAR OBJECTS

Albert Schuitema, Amsterdam, Netherlands

Application February 11, 1953, Serial No. 336,385

3 Claims. (Cl. 209—97)

1

This invention relates to an apparatus for separating and, if desired, sorting flat circular objects, for example, pharmaceutical tablets or coins, in which a segment-shaped marginal portion of a counting disc rests on a horizontal feeding surface which is movable in a horizontal direction within a confining wall, which counting disc has its circumference provided with incisions, the side walls of which, in the same sense make a sharp angle with the circumference of the disc and which disc, fitting within a ledge partly surrounding it, is mounted on a vertical shaft for rotation over a support comprising one or a plurality of discharge apertures adapted to be brought into register with the incisions of the counting disc, said counting disc being so coupled with a driving mechanism that when the apparatus operates normally the undercut said edges of the incisions are the leading ones.

An apparatus of this type is known. In this known apparatus which has the above features, the feeding surface is an endless belt, the upper part of which is supported by a horizontal table, while a counting disc is provided at the discharge side of said conveyor belt. It was found that in an apparatus of this construction the filling of the counting cavities does not always proceed regularly.

This complication can be avoided if according to the invention the feeding surface is formed as a disc mounted for rotation about a vertical shaft, the driving mechanism of said disc and of the counting disc as well as the undercut side edges of the incisions in the counting disc in conjunction with the ledge confining said disc being so designed that when the apparatus operates normally the two discs move in the same direction at the place where they overlap, the feeding disc moving at a higher speed than the counting disc, and that furthermore the flat circular objects lying on the feeding disc are removed therefrom by the counting disc.

In a practical embodiment of the apparatus according to the invention the circumference of the circular counting disc crosses the circumference of the likewise circular feeding disc at an angle of about 90°.

The invention will be elucidated with reference to the accompanying drawing, showing some embodiments. Though the apparatus is suited for handling all kinds of flat circular objects I shall for the sake of simplicity only speak of coins hereinafter.

Fig. 1 is a plan view of an apparatus for separating coins of different diameters.

2

Fig. 2 is a section of the rotatable feeding disc and of the counting disc taken on the line II-II in Fig. 1.

Fig. 3 shows the counting disc in another position.

Fig. 4 shows a sorting aperture at the moment when a coin meant for this aperture arrives over it and

Fig. 5 shows a sorting aperture across which a coin of larger diameter is passed.

Fig. 6 shows a counting cavity capable of containing a plurality of coins at a time, said cavity having its leading edge provided with a number of recesses.

15 In the apparatus shown in Figures 1 and 2 the reference numeral 1 designates a rotatable flat feeding surface which is a circular disc here, on which the coins are spread out. This feeding disc is mounted on a shaft 3 by means of a flange 2 and can be rotated in the direction of the arrow. A circular counting disc 4 having counting cavities recessed in its circumference is mounted on a shaft 5 by means of a flange 6, the lower side of this counting disc being level with the upper side of the feeding disc 1. This counting disc is provided with slots 7 and 8 which register with raised engaging elements on the flange 6. By means of a nut 9 the disc 4 is kept pressed against the flange 6 and against the upper side of the feeding disc 1.

20 The shaft 5 is parallel to the shaft 3 and in the present embodiment the former is coupled with the latter by means of gears 10 and 11, so that the directions of movement of the feeding disc 1 and the counting disc 4 are equal at the place of contact between these discs. The pitch circle of the gear 11 secured to the shaft 5 is larger than the diameter of the disc 4, so that at each point of contact between the disc 4 and the feeding disc 1 the speed of movement of the latter disc is larger than that of the counting disc 4.

25 Below the counting disc 4 a stationary plate 12 is provided which links up with the circumference of the feeding disc 1 and on which plate a ledge 13 is secured which annularly surrounds the counting disc 4 and which to the left in Figure 1 partly overlies the feeding disc 1.

The plate 12 and the annular ledge 13 are secured on a stationary plate 14, which plate at the same time serves to support the feeding disc 1. Furthermore an annular wall 15 is provided on the plate 14, which wall prevents the coins lying on the feeding disc 1 from being hurled off said disc by the centrifugal force.

The coins spread out on the feeding disc 1 in a single layer are forced against the circumference of the counting disc 4 by the rotating movement of the feeding disc 1, so that the counting cavities in the counting disc 4 are filled with coins, while the coins that are not received in a counting cavity are passed along the circumference of the counting disc 4 by the movement of the feeding disc 1 and are used for a subsequent counting.

Initially the coins introduced into the counting cavity are moved towards the center of the disc 4, and therefore, forced against the bottom of the counting cavity. According as during the rotation the counting cavity lags behind relatively to the feeding disc 1 the coins, however, are urged towards the leading edge of the counting cavity.

At the place where the leading edge of the counting cavity intersects the circumference of the counting disc this edge forms an angle which is smaller than 90° with the tangent to the circumference of the disc so that the counting cavity may be said to be undercut relatively to the feeding disc 1. The coins contained in the counting cavity will remain in engagement with the leading edge thereof owing to the feeding disc 1 rotating at a higher speed than the counting disc 4 and owing to the shape of this leading edge, as described, they will remain in this counting cavity until an imaginary line in alignment with the leading edge of the counting cavity passes through the center of the feeding disc 1. Approximately from this place onwards the curved ledge 13 extending over the plate 1 is provided along the circumference of the disc 4, which ledge prevents the coin contained in the counting cavity from being again removed therefrom by the rotating movement of the disc 1. Other coins which were contained in the counting cavity but which did not find an accommodation against the leading edge thereof have previously been taken along by the rotating movement of the feeding disc 1 or are removed from the cavity past the wedge-shaped end of the ledge 13 by the more rapid movement of the feeding disc 1. Thus always but one coin is separated by each counting cavity, as may be seen from Figure 3.

It will be clear that for a proper operation of the apparatus which requires that each time only one coin be separated by a counting cavity, the difference in diameter of the coins to be sorted is limited. If, for example, the diameter of the smallest coins is less than half the diameter of the largest coins it might occur that two small coins are still contained in the counting cavity after this cavity has passed the extremity of the curved ledge 13.

The leading edge of the counting cavities instead of being rectilinear can also be curved, in such a manner that the angle formed by a tangent to this curved leading edge and the outer circumference of the counting disc 4, at the place where these lines intersect, is smaller than all other angles formed by tangents to this curved leading edge and the outer circumference of the counting disc 4. Counting cavities of such a design also render it possible to separate and to count irregularly shaped discs, such as e. g. oval tablets.

When the counting disc 4 continues its movement the coins are first slid across the feeding disc 1 rotating below the counting disc and after the circumference of the feeding disc 1 has been

passed they are taken over and passed further across the stationary plate 12. At the place where the trailing edge of the counting cavity intersects the circumference of the counting disc 4 this edge forms with the tangent to the circumference of the counting disc 4 an angle which is larger than 90°.

As a result the coin which is moved along by this trailing edge of the counting cavity is kept forced against the inner edge of the ledge 13.

Along the inner edge of the ledge 13 sorting apertures 16, 17, 18, 19 and 20 are provided in the plate 12, by means of which, therefore, five kinds of coins of different diameters can be sorted. The outer edge of said apertures (as seen looking from the center of the disc 4) is located at a small distance from the inner edge of the ledge 13, so that a support for the passing coins is formed. The distance from the inner edge of the aperture 16 to the inner edge of the ledge 13 is slightly larger than the diameter of the smallest coins, so that said smallest coins upon passing the aperture will tilt and drop therein and are thus separated, as is shown in Figure 4.

Coins of a larger diameter, however, will also be supported on the inner side of the aperture and are passed across the aperture by the counting disc 4, as is shown in Figure 5.

From the remaining coins the coins of the smallest diameter are again separated by the subsequent sorting aperture 17 and so on until the coins of the largest diameter drop through the last aperture 20.

The coins dropping through the sorting apertures can be counted when they slide through a discharge funnel, this counting may be effected by means of an electric contact or a photo-electric cell. In this manner all the different kinds of coins supplied by the counting disc 4 are sorted according to their diameter and at the same time the numbers of each kind of coin are separately recorded.

It is also possible only to sort the coins of different diameters in the manner described above and subsequently to separately count the coins of equal diameter. This can be effected by again separating these coins of equal diameter one by one by means of a round disc having a counting cavity and to pass these coins to a discharge funnel, provided on the inside of the ledge 13 in the plate 12. This counting can be effected by means of an electric contact or a photo-electric cell, whereby a counting mechanism is operated each time when a coin passes.

This counting can also be effected mechanically if the round counting disc with counting cavities is automatically brought to a standstill by a stopping device each time after a given number of coins has been deposited in the discharge funnel.

Figure 6 finally shows a counting disc having a counting cavity, in the leading edge of which three recesses are provided. This counting disc is suited to separate three coins at a time.

I claim:

1. An apparatus for separating and, if desired, sorting flat circular objects, in which a segment-shaped marginal portion of a counting disc rests on a horizontal feeding surface which is movable in a horizontal direction within a confining wall, which counting disc has its circumference provided with incisions, the side walls of which, in the same sense make a sharp angle with the circumference of the disc and which disc, fitting

within a ledge partly surrounding it, is mounted on a vertical shaft for rotation over a support comprising one or a plurality of discharge apertures adapted to be brought into register with the incisions of the counting disc, said counting disc being so coupled with a driving mechanism that when the apparatus operates normally the undercut side edges of the incisions are the leading ones, characterized in that the feeding surface is formed as a disc mounted for rotation about a vertical shaft, the driving mechanism of said disc and of the counting disc as well as the undercut side edges of the incisions in the counting disc in conjunction with the ledge confining said disc being so designed that when the apparatus operates normally the two discs move in the same direction at the place where they overlap, the feeding disc moving at a higher speed than the counting disc, and that furthermore the flat circular objects lying on the feeding disc are removed therefrom by the counting disc.

2. An apparatus as claimed in claim 1, charac-

terized in that the circumference of the circular counting disc crosses the circumference of the likewise circular feeding disc at an angle of about 90°.

3. An apparatus as claimed in claim 1, characterized in that above the rotary flat feeding surface at the circumference of the counting disc an extension of the ledge surrounding the counting disc is arranged in such a manner that said extension prevents a flat circular object or objects from being removed out of the counting cavity by the subjacent feeding surface during the rotation of said counting disc.
